BASEBALL GAME BOARD WITH SLIDING PANEL

Berthold V. Marschke, Lucca, N. Dak.

Application November 24, 1948, Serial No. 61,885

4 Claims. (Cl. 273—93)

1

My invention relates to an improvement in games and deals particularly with a type of game which simulates a game of baseball.

Many games have been produced which simulate the games of baseball, football, and the like. Certain of these are equipped with a game board which indicates the playing field and includes playing elements which may be placed on the playing field so that the position of the players during the game may be immediately noted. Such games have the difficulty that it is necessary to move these playing pieces after each play in the game and as several playing pieces are often involved there is a considerable chance of mistake. Furthermore, if the playing field is accidentally jarred or moved the position of the playing elements often becomes changed, thereby making it impossible to determine the previous location of the playing elements except by memory.

An object of the present invention lies in the provision of a game simulating the game of baseball which incorporates a playing field having apertures therethrough at locations corresponding to first, second and third bases and which includes a movable element beneath the game table which may be moved to indicate players on any of the bases mentioned. The movable element beneath the game table is preferably of a color which contrasts with the color of the game table and as the movable member moves beneath the game table a different contrasting color is visible in one or more of the apertures to indicate various combinations of players on the playing field.

A feature of the present invention lies in the provision of a game table having apertures therein and in the provision of a movable game element which is visible through the various apertures to indicate predetermined combinations of positions of the players upon the playing field. Indicia on the movable element is also visible through apertures in the playing field and the visible indicia corresponds to the position of the players on the playing field.

A feature of the present invention lies in the provision of a game table having a slide movable therebeneath and visible through apertures in the playing table. When no players are on base the indicia visible through certain of the openings indicate possible plays which may take place while the bases are empty and also the apertures adjacent the bases on the playing field indicate that no players are on base. The plays listed on the slide and visible through apertures in the

2

playing field are numbered or otherwise identified so that a chance selector of any desired type may be actuated to select any of the plays exposed. Once the selector has selected a predetermined play the slide is moved beneath the game table until the apertures adjacent the bases show the results of the play in the event the situation is changed as a result of the selected play.

A feature of the present invention lies in the provision of a game table having a playing field indicated thereon and having apertures adjacent each of three bases on the field and in providing a movable element having lists of plays which can take place under various circumstances. For example at the start of the game the slide is moved until the apertures adjacent the bases indicate that no player is on base and the list of plays exposed are plays which may take place while the bases are empty. If, as a result of the operation of the play selector, it is determined that a player reaches first base, the movable element is moved until an area of contrasting color or some other identifying indicia is visible through the aperture adjacent first base. This movement of the movable element also exposes a second list of plays which may take place logically while the player is on first base. The movable element may also be actuated to indicate a player on second base with first and third bases empty, a player on third base with first and second bases empty, players on first and second bases, players on first and third bases, players on second and third bases and the bases filled. By merely moving the movable member until the players are indicated at the proper locations on the playing field, a list of indicia is exposed showing plays which may logically take place while the players are in the position illustrated.

Another feature of the present invention lies in the fact that my lists of plays are arranged in identical columns, half of which are inverted relative to the others so that the plays may be readily seen from either side of the game table. As a result the game may be played by two players sitting in opposed relation without the necessity of changing the position of the playing field.

These and other objects and novel features of my invention will be more clearly and fully set forth in the following specification and claims.

50 In the drawings forming a part of my specification:

Figure 1 is a top plan view of my game showing the general construction thereof.

55 Figure 2 is a plan view of the movable slide positioned beneath the game table.

Figure 3 is a longitudinal section through the game, the position of the section being indicated by the line 3—3 of Figure 1.

The game A may be formed in various manners, the construction shown in the drawings being typical of such arrangements. The game A illustrated includes an open ended envelope 10 which encloses a flat slideable member 11. The envelope 10 includes a top panel 12 and a bottom panel 13, these panels 12 and 13 being foldably connected together along the longitudinal edges 14 and 15.

The top panel 12 is provided with a pointer 16 pivotally connected at 17 thereto and which is rotatable in a circular path. A ring 19 encircles the pointer 16 and is concentric therewith. This ring 19 is divided into a series of short sections or segments which are both of equal length, although the length of the segments may be varied if desired. Identifying indicia 20 is provided in the various sections of the ring 19, the sections being separated by radially extending partition lines 21.

The pointer 16 may be operated in a manner known in the art by merely propelling the pointer about its pivot 17, the pointer gradually slowing until it comes to rest in position to indicate one of the numerals or other identifying means 20. In the particular structure illustrated the ring 19 is divided into 27 segments of equal length.

A pair of rows of apertures indicated in general by the numerals 22 and 23 are located in spaced parallel relation upon the upper panel 12 of the envelope 10. These rows of apertures 22 and 23 each comprise four separate spaced apertures spaced by a narrow spacing band. The row of apertures 22 includes transversely spaced and aligned apertures 24, 25, 26, and 27. The apertures 24 and 25 are connected by a bridge strip 29. The apertures 25 and 26 are connected by a bridge strip 30. The apertures 26 and 27 are connected by a bridge strip 31. Similarly the row of apertures 23 includes four laterally spaced and aligned apertures 32, 33, 34 and 35. The apertures 32 and 33 are separated by a bridge strip 36. The apertures 33 and 34 are separated by a bridge strip 37. The apertures 34 and 35 are separated by a bridge strip 39. It is important to note that the strips 29 and 36 are aligned, the bridge strips 30 and 37 are aligned and the bridge strips 31 and 39 are longitudinally aligned in the top panel 12.

A playing field is designated on the panel 12 between the rows of apertures 22 and 23. This playing field includes a rectangular infield designation indicated in general by the numeral 40. The playing field includes a representation of a pitcher's mound 41 and a catcher's position 42 which is directly behind the batting box 43. A right field foul line 44 extends in one direction from the batting box 43 and a left field foul line 48 extends outwardly at right angles to the foul line 44. The foul line 44 in part forms the base line between the batter's box and home plate 43, and first base 46. A second base line 47 extends from first base at right angles to the foul line 44 to the second base representation 48. A third base line 49 extends from second base 49 to third base 50 at right angles to the left field foul line 45.

The base representations for first base 46, second base 48 and third base 50 comprise rectangular apertures in the panel 12 and it is important that these apertures are longitudinally aligned with the various bridge strips separating the apertures in the rows of apertures 22 and 23.

The aperture 46 is longitudinally aligned with the bridge strips 29 and 36. The aperture 48 is longitudinally aligned with the bridge strips 30 and 37. The aperture 50 is longitudinally aligned with the bridge strips 31 and 39. As a result portions of the slideable member 11 which are visible through the base apertures 46, 48, and 50 are concealed from view through the rows of apertures 22 and 23.

Each row of apertures 22 and 23 is provided with an adjacent row of indicia, the row of indicia 51 being adjacent the row of apertures 22 and the row of indicia 52 being adjacent the row of apertures 23. Each of the apertures of each row is divided by the rows of indicia 51 and 52 into seven sections. The aperture 21 includes an undesigned section 53 and six designated sections designated by indicia 54 which corresponds with indicia 20 of the ring 19. For example in the construction shown the top one-seventh of aperture 21 is undesigned to provide a space through which a column head may be seen while the remaining six-sevenths of the aperture is identified by the numbers 1 to 6. The aperture 26 is divided into seven equal spaces designated by indicia 55 which in the present construction comprises the numerals 1 through 12 inclusive. The aperture 25 is divided into seven equal spaces designated by indicia 56 which in the construction shown comprises numerals 14 to 20 inclusive. The aperture 22 is divided into seven equal spaces which in the arrangement shown comprises the numbers 21 through 27 inclusive as shown at 57.

The indicia 52 is similarly arranged relative to the row of apertures 23. The transverse length of the aperture 32 is divided into seven equal spaces, the first of which remains unidentified to accommodate a column title on the slideable member 11. The remaining portion of the aperture bears identifying indicia 59 which in the construction shown comprises the numerals 1 to 6 inclusive.

The aperture 33 is divided into seven equal spaces which are identified by indicia in the indicia column 52 indicated specifically at 60. The indicia 60 in the construction illustrated comprises the numbers 7 to 13.

The transverse length of the aperture 34 is likewise divided into seven equal spaces which are identified by indicia in the indicia column 52 indicated specifically at 61, which in the construction shown comprises the numbers 14 through 20 inclusive. Similar indicia is provided adjacent the aperture 35 and this aperture is divided into seven spaces which in the form shown are identified by numerals 21 through 27 inclusive.

The slide 11 is illustrated in some detail in Figure 2 of the drawings. This slide comprises a generally rectangular body having a pair of projecting end tabs 63 and 64. The body of the sheet 11 is preferably about the same in length as the envelope 10 and the tab 63 provides a means of sliding the sheet when thus telescoped.

The sheet 11 is divided into sixteen separate columns in length, a short end portion 65 of the sheet projecting beyond the columns to overlie the portion of the envelope panel 12 between the row of apertures 22 and the adjacent end of the envelope. The sixteen columns are divided into two halves, indicating eight of the columns on one end of the sheet reading toward one edge 66 thereof while the indicia on the remaining eight columns at the other end of the sheet read to-

ward the edge 67 thereof. The columns extend to a point spaced from the edges 66 and 67 of the sheet, providing unprinted margins 69 and 70 on the portion of the sheet which extends laterally beyond the rows of apertures mentioned.

Each of the columns are divided into thirty-one sections which may be of equal size. The first seven spaces of each column include indicia to indicate a play, with the exception of the top space of the column which bears a heading indicating the position of the runners on the bases. The eighth space of each column does not bear any indicia showing a play as this space is normally covered by certain of the bridge strips. The 9th to 15th spaces inclusive of each column bear indicia indicating a suitable play. The 16th space bears no play indicia as this space is normally covered by certain of the bridge strips. The seventeenth to the twenty-third space inclusive of each column includes indicia indicating a suitable play. The twenty-fourth space of each column bears no such indicia as this space is normally covered by the bridge strips. The twenty-fifth to the thirty-first space of each column bears indicia which indicates logical plays. The indicia which does appear in the eighth, sixteenth, and twenty-fourth spaces of each column will be later described in more detail.

The first column 70 at one end of the sheet and the corresponding first column 71 at the other end of the sheet contain indicia describing plays which may take place when the bases are empty and the columns 70 and 71 are headed by the title "bases empty" indicated by the numeral 72. Thus when the columns 70 and 71 are in registry with the rows of apertures 22 and 23 in the panel 12, the game is in position for plays which might take place when the bases are empty. At this time the apertures 46, 48 and 50 in the panel 12 disclose blank spaces on the sheet 11 or expose portions of the sheet 11 bearing suitable indicia to indicate that the bases are empty. In the form of construction shown blank areas of the sheet 11 which is of a contrasting color from the envelope 10 appear through these apertures.

The second column 73 at one end of the sheet and the corresponding second column 74 at the opposite end of the sheet lists a series of plays which may take place while a player is on first base. This column bears a heading "player on first" indicated by the numeral 75 in Figure 2 of the drawings. While the columns 73 and 75 are in registry with the rows of apertures 22 and 23 respectively, a portion of contrasting color on the sheet 11 is visible through the first base aperture 46. For example the color red which contrasts with the colors of the envelope and of the sheet 11 may be visible through the first base aperture 46 when the sheet 11 is in this position.

The third column 76 at one end of the sheet and the corresponding third column 77 at the other end of the sheet bear indicia listing plays which may take place while a player is on second base and while the other bases are unoccupied. These columns 76 and 77 are headed by the statement 79 "player on second." While the columns 76 and 77 are in registry with the apertures 22 and 23 of the envelope 10, the previously exposed contrasting portion visible through the first base aperture 46 moves out of registry with this aperture and a contrasting colored area on the sheet 11 is visible through second base aperture 48. Thus looking at the playing field any player would note that second base is occupied while first

and third bases are not. The fourth column 80 at one end of the sheet 11 and the corresponding fourth column 81 at the other end of the sheet list plays which may logically occur while a player is on third base and the other bases are unoccupied. These columns are headed by the words "player on third" indicated in Figure 2 by the numeral 82. While the sheet is in position to expose the columns 80 and 81 through the rows of apertures 22 and 23 the contrasting color visible through second base aperture 48 disappears and a colored area becomes visible through third base aperture 50. The slide member 11 is shown in this position in Figure 1 of the drawings.

The fifth column 83 at one end of the sheet and the corresponding fifth column 84 at the other end thereof bear plays which might logically take place while players are located on both first and second bases. These columns are headed by the title "players on first and second," indicated by the numeral 85. When the slide 11 is moved into position to expose the colors 83 and 84 through the rows of apertures 22 and 23 respectively, the colored indication disappears from view through aperture 50 and a suitable contrasting color indication appears through apertures 46 and 48. Thus when the plays which might take place while a player is on first and second are listed in the rows of apertures, a color indication is provided on the playing field showing the location of players at these bases.

The sixth column 86 at one end of the sheet 11 and the corresponding sixth column 87 at the other end of the sheet list plays which might logically take place while players are on first and third bases. These columns are headed with indicia 89 which specify "players on first and third." While the sheet 11 is in position to expose the columns 86 and 87 through the rows of apertures 22 and 23 the color indication previously visible through second base aperture disappears and a color indication is visible through apertures 46 and 50 indicating men on first and third bases of the playing field.

The seventh column 90 at one end of the sheet and in the corresponding seventh column 91 at the opposite end of the sheet are listed plays which might logically take place while players are located on second and third bases. These columns are headed by indicia 92 specifying "players on second and third."

While the sheet 11 is in position to expose the columns 90 and 91 through the rows of apertures 22 and 23, color indications indicating men on these bases are visible through apertures 48 and 50 in the panel 12.

In the eighth column 93 at one end of the sheet and in the corresponding eighth column 94 at the other end thereof plays are listed which may logically take place while the bases are loaded. These columns are provided with suitable indicia 95 which states "bases filled." While the sheet 11 is in this position a colored indication is visible through all of the apertures 46, 48 and 50.

The various color indications described are located in the eighth, sixteenth and twenty-fourth spaces of the various columns which are normally concealed by the bridge strips. These color indications which are visible through the aperture 46 are indicated by the numeral 96. The colored indications which are visible through the aperture 48 are indicated by the numeral 97. The color indications which are visible through the aperture 50 are indicated by the numeral 99. These colored areas 96, 97, and 99 are properly

spaced to register with the apertures named in the correct position of the sheet 11.

The manner in which the game is played will be understood from the foregoing description. The sheet 11 is first placed in position with the columns 10 and 11 in registry with the rows of apertures 22 and 23, the bases being empty at the beginning of the game. One player representing one team then spins the pointer 16 and determines the play corresponding to the number to which the pointer points. The player may obtain a strike, a ball, or a foul and these strikes and balls are counted as in the game of baseball. If the player gets three strikes, he is counted out as in baseball. If the player reaches first base, the slide 11 is moved until the colored indication appears in aperture 46 and in no other aperture. The columns 13 and 14 of the sheet 11 are then exposed through the rows of apertures 20 and 23. Similarly it is possible for the player to get a two-base hit, a three-base hit, or a home run and the slide 11 is moved accordingly.

If the player is successful in reaching a base, the slide 11 is moved to provide the proper indication in the base apertures and to move the desired columns into registry with the rows of apertures. The pointer is then actuated to see what plays will occur. Obviously the possible plays change without change in location of the players as it is possible to make a double play when a player is on first base, but is less likely when a player is on second or third base.

As soon as the player has three men called out the slide 11 is placed to its original position and the other player begins to play. The game is played in innings similarly to a regular game of baseball.

In accordance with the patent statutes, I have described the principles of construction and operation of my game, and while I have endeavored to set forth the best embodiment thereof, I desire to have it understood that obvious changes may be made within the scope of the following claims without departing from the spirit of my invention.

I claim:

1. A base ball game including a game board having the representation of a base ball field thereon and having apertures therethrough adjacent the representation of first, second and third bases, said game board also having an elongated aperture therethrough extending substantially across the game board adjacent to the representation of the field, a slidable member supported for sliding movement beneath said game board in a direction transversely of said elongated aperture, said slidable member being visible through said apertures, a series of symbols on said game board spaced longitudinally of said elongated aperture, said slidable member being slidable through a series of positions, indicia on said slidable member visible through the aperture adjacent the representation of first base in one of said positions to indicate a runner on first base, spaced legends on said slidable member, one legend being adjacent each of said symbols, visible through said elongated aperture in said one position and representing possible occurrences which may take place while a runner is on first base, indicia on said slidable member visible through said aperture near the representation of second base in a second position of said slidable member to indicate a runner on second base, a

series of spaced legends on said slidable member visible through said elongated aperture in said second position of said slidable member and representing possible occurrences when a runner is on second base, one of said last named spaced legends being adjacent each of said symbols, indicia on said slidable member visible through the aperture near the representation of third base in a third position of said slidable member, a series of spaced legends on said slidable member visible through said elongated aperture in said third position, said last named spaced legends being adjacent to said spaced symbols, and representing possible occurrences when a man is on third base.

2. A base ball game including a game board having the representation of a base ball field thereon and having apertures therethrough adjacent the representation of first, second and third bases, said game board also having an elongated aperture therethrough extending substantially across the game board adjacent to the representation of the field, a slidable member supported for sliding movement beneath said game board in a direction transversely of said elongated aperture, said slidable member being visible through said apertures, a series of symbols on said game board spaced longitudinally of said elongated aperture, said slidable member being slidable through a series of positions, indicia on said slidable member visible through said apertures near the representation of the bases to indicate base runners in various combinations of locations, one combination being visible in each of said positions of said slidable member, and a different row of indicia visible through said elongated aperture in said game board in each position of said slidable member, each said row of indicia including a series of spaced legends equal in number to, and corresponding in position to, said symbols, the row of indicia visible in each position of the slidable member indicating possible occurrences which may take place when the base runners are in the corresponding locations indicated through the apertures near the base representation while the slidable member is in that position.

3. The structure defined in claim 2 in which the indicia visible through the apertures near the base representations traverses the elongated aperture upon slidable movement of the slidable member, and including bridge portions across said elongated aperture to conceal this last named indicia.

4. The structure defined in claim 2 and in which the playing field is arranged with a center line from home plate to second base at an angle to the direction of the elongated aperture.

BERTHOLD V. MARSCHKE.
